DRY SEAL PRESSURE TYPE
GAS HOLDER

John H. Wiggins, Chicago, Ill.

Application November 18, 1947, Serial No. 786,578

2 Claims. (Cl. 48—178)

1

This invention relates to dry seal, pressure-type gas holders of the particular kind in which the piston is provided with an opening for receiving a vertically-disposed roof support, said opening being sealed by a flexible, curtain-like sealing element of approximately tubular form in general shape or outline, attached at one end to the piston and having its other end attached to said roof support at a point substantially mid-way the extreme upper and lower positions of the piston.

One object of my invention is to provide a gas holder of the general kind above referred to, in which the sealing element for the opening of the piston is so constructed and arranged that the internal gas pressure in the storage space or chamber of the apparatus supports said sealing element and lifts said element during the upward stroke of the piston.

Another object of my invention is to provide a gas holder of the general kind above referred to, in which substantially the entire horizontal projection of the sealing element for the roof support opening of the piston is utilized as the area of said sealing element to which the gas pressure is applied for lifting said element.

And still another object of my invention is to provide a gas holder of the general kind above referred to, in which the roof support that extends through the piston is provided with an abutment portion or backing surface for the previously mentioned center sealing element, so constructed and arranged that during the upward stroke of the piston, the internal gas pressure causes the major portion of the area of said center sealing element to lie snugly against said backing surface, substantially free of wrinkles. Other objects and desirable features of my invention will be herein-after pointed out.

Figure 1 is a vertical transverse sectional view of a dry seal, pressure-type gas holder constructed in accordance with my invention.

Figure 2 is a fragmentary, vertical transverse sectional view, showing the piston slightly above the mid-way point of its extreme upper and lower positions; and

Figure 3 is an enlarged, fragmentary sectional view, illustrating the action of the gas pressure on the sealing element for the center opening of the piston, during the upward stroke of the piston, and showing how said sealing element is applied progressively to the tapered or frusto-conical-shaped abutment portion or backing surface of the center roof support.

In the accompanying drawings, which illus-

2

trate my invention applied to a dry seal, pressure-type gas holder whose piston constitutes the top wall of the gas storage space or chamber, the reference character A designates the roof of the casing, B designates the side wall of the casing, C designates the bottom of the casing, which also forms the bottom of the gas space, D designates the piston, I designates a flexible, curtain-like element of gas-tight material secured at one edge to an attaching device 4 on the side wall and secured at its other edge to the peripheral edge portion of the piston, so as to seal the annular space between said side wall and piston, E designates an upwardly-projecting fender or abutment member on the piston which absorbs forces exerted by the gases on the sealing element I and also causes said sealing element to assume a predetermined approximate shape or form during the rise and fall of the piston, II designates a venting device on the roof, and 16 designates a gas-inlet. The parts above described are of conventional construction and form no part of my present invention.

It is old in this art to equip a gas holder of the general kind above described with a center roof support that extends vertically through an opening in the center of the piston, and seal said center opening by means of a flexible, curtain-like sealing element attached to the piston and to said center roof support, but in such prior structures the sealing element for the center opening in the piston, and the center roof support, were constructed in a different manner and functioned in a different way than the corresponding parts of the herein described gas holder which constitutes my present invention. In Figure 1 of the drawings the reference character F designates, as an entirety, a vertically-disposed, tubular member at the center of the casing that serves as a support for the roof A and also serves as a housing for a weight 10 suspended from cables or the like 7 attached to the piston D and arranged to travel over overhead pulleys or guide wheels 8 and 9. Said roof support F extends upwardly through a center opening in the piston, and said center opening is sealed by a flexible, curtainlike element 2, which is preferably constructed in the form of a frustum of a cone. The small end of said frusto-conical sealing element 2 is secured by fastening devices 5 and a seal bar 17 to the center roof support F at a point approximately mid-way the two extreme positions of the piston, and the large end of said sealing device 2 is attached by fastening devices 55 12 to a collar 6 on the top side of the piston,

which surrounds the center opening in the piston. The center roof support F is provided with a lower portion 13 that is gas-tight from its extreme lower end up to the point where the small end of the center sealing element 2 is attached to said roof support, said lower portion 13 being cylindrical or of any other preferred cross-sectional shape. Above the point of attachment of the sealing element 2 to the center roof support F, said support flares outwardly so as to form an inverted frusto-conical abutment member or back stop surface 14 for the center sealing element 2 when the piston is at the end of its upward stroke. The upper portion 15 of the roof support may be cylindrical or of any other preferred cross-sectional shape. The upper portion 15 and the tapered back stop portion 14 of the roof support F do not have to be gas-tight, inasmuch as both of said portions of the roof support are located outside of the gas storage space of the holder.

When the piston is at or adjacent the end of its downward stroke, as shown in solid lines in Figure 1, the gases in the storage space or chamber exert a force on the center sealing element 2, as indicated by the arrows, with the result that said sealing element 2 is supported by the internal pressure. During the upward stroke of the piston, the gas pressure lifts the entire sealing element 2, holds the lower portion of said sealing element in tension, and progressively applies said sealing element to the tapered back-stop or abutment surface 14 of the center roof support F, as shown in Figures 2 and 3. By the time the piston has reached its extreme upper position, as shown in broken lines in Figure 1, the major portion of the area of the sealing element 2 will lie snugly against the inverted, frusto-conical portion 14 of the roof support F, substantially free from wrinkles, and the portion of said sealing element that bridges the space between the portion 14 of the roof support and the attaching collar 6 on the piston will be maintained in the form of an upwardly-disposed loop by the gas pressure in the storage space. The sealing element 2 operates in the manner above described, because said sealing element is built as a conical frustum to fit a special condition, the area of the annular space 8 being dependent on the weight of the element 2 and the internal pressure of the gas storage space. The product "gas pressure per square foot times the area Y equals the weight of the sealing element 2" is the formula which determines the width of the annular space Y. It can thus be seen that varying space Y gives control for variable pressures and variable weights of the sealing element 2.

So far as my broad idea is concerned, it is immaterial whether the roof support is located at the center of the casing, or at a point between the center and side wall of the casing. It is also immaterial whether the gas holder is provided with only one roof support, or a plurality of roof

supports that project upwardly through openings in the piston, adapted to be sealed by flexible, curtain-like sealing devices embodying my invention.

Having thus described my invention, what I claim as new and desire to secure by Letters Patent is:

1. A dry seal, pressure-type gas holder whose casing comprises a vertical side wall and a roof, a vertically-reciprocating piston in said casing, a flexible, gas-tight sealing means disposed between said side wall and the peripheral edge of the piston, a vertically-disposed support for said roof that projects upwardly through an opening in the piston, a flexible, curtain-like sealing element of substantially frusto-conical form having its large end attached to the piston adjacent the opening in same and having its small end attached to said roof support mid-way the extreme upper position and lower position of the piston, and an abutment surface of inverted frusto-conical form on said roof support, arranged so as to serve as a backing for said frusto-conical-shaped sealing element when the piston is in its extreme upper position, said abutment surface beginning adjacent the point of attachment of the said sealing element to said roof support and widening upwardly above said point of attachment.
2. A dry seal, pressure-type gas holder, having a casing that comprises a roof and a vertical side wall, a vertically-reciprocating piston in said casing, a flexible, gas-tight sealing means disposed between said side wall and the peripheral edge of the piston, a vertically-disposed support for said roof that projects upwardly through an opening in said piston, a flexible, curtain-like sealing element of substantially frusto-conical form for sealing the roof support opening in the piston, attached to the piston and to the roof support, and an abutment surface of substantially inverted frusto-conical form on said roof support located above the point of attachment of the sealing element to the roof support, said sealing element being arranged so that during the upward stroke of the piston the internal gas pressure presses the major portion of said sealing element into snug engagement with the said abutment surface on the roof support and causes the portion of said sealing element immediately adjacent the opening in the piston through which said roof support extends, to assume the form of an upwardly-disposed loop.
